MISSILE LAUNCHING SYSTEM

Sven Landstrom, Stockholm, Sweden, assignor to the United States of America as represented by the Secretary of the Navy

Filed Oct. 22, 1958, Ser. No. 769,042

2 Claims. (Cl. 89—1.7)

(Granted under Title 35, U.S. Code (1952), sec. 266)

The invention described herein may be manufactured and used by or for the Government of the United States of America for governmental purposes without the payment of any royalties thereon or therefor.

This invention relates to an improved system for launching guided missiles and more particularly to an improved system and methods of use thereof for the launching of guided missiles from a land base.

Experience with launching methods and apparatus systems designed for launching guided missiles has demonstrated the need for a new type equipment for magazining, handling and launching present day guided missiles. In my copending application, Serial No. 769,045, filed Oct. 22, 1958, I have disclosed a system and a method of use thereof suitable for handling the complex weapons usable today for national defense. The instant invention is an improvement of my aforementioned system and methods.

The difficulties encountered in effectively using todays guided missiles stem from the excessive size and weight of the missiles coupled with their inherent structural and operational delicacies. To successfully assemble and maintain adequate supplies of present day missiles in a ready status and to launch those missiles in the most expeditious fashion when the occasion arises, requires a complete departure from previous thinking in the magazining, handling and launching techniques used with former conventional weapons.

Accordingly, it is an object of the present invention to provide an improved magazining, handling and launching system and method of use thereof for guided missiles which allows selectability of missiles for launching according to desires as to warhead type, guidance system and propulsion means, from a roundhouse magazine.

A further object of the invention is to provide an improved launching system for either surface-to-surface or surface-to-air guided missiles which is adapted for single or salvo firing.

Another object resides in the provision of a launching and magazining system which overcomes the shortcomings of prior art fixed launching systems while providing substantially all the desirable practical functional and safety features of apparatus for this purpose heretofore or now in general use.

Still another object of the invention is to provide a safe, simple and expeditious method and system for handling, storing and launching guided self-propelled missiles.

Other objects and many of the attendant advantages of this invention will be readily appreciated as the same becomes better understood by reference to the following detailed description when considered in connection with the accompanying drawings wherein:

FIG. 1 is a plan view of approximately one-half of a launching system incorporating the present invention with the roof being omitted from the circular magazine to more clearly illustrate details of the invention;

FIG. 2 is an enlarged elevational view with parts shown in section and as viewed from a line substantially corresponding to line 2—2 in FIG. 1;

FIG. 3 is a perspective view showing a missile transporting cart; and

FIG. 4 is a side elevational view with parts shown in section, the section being taken through the launching

2

pit along a plane corresponding to the direction of the ramming rail of the magazine and with the launcher in loading position.

In FIG. 1 is illustrated one half of a system incorporating this invention, it being understood that the other half, comprising a mirror image of FIG. 1 may be located along the broken away left side of FIG. 1. As there shown a circular magazine 14 incorporates a plurality of radially disposed individual missile stowage cells 15 in which assembled missiles 23 are stored with the warhead ends directly outwardly. The individual cells 15, each contain a feeder rail 20 and are separated from each other by spaced walls 16 the space therebetween being provided with a blast dissipating substance 22, such as sand, to contain any premature explosion in as small an area as possible. The inner periphery of the circular magazine 14 is formed by individual blast closures or doors 17 isolating each missile stowage cell 15 from the turntable area located centrally within the magazine. At the center of the magazine is provided a pivot post 19 about which the magazine turntable 12 rotates. The outer periphery of the circular magazine is bounded by an external wall 11, which like the other structural components of the magazine may be formed of reinforced concrete or the like.

The individual blast doors 17 located on the inner periphery of the magazine are mounted to reciprocally move along stanchions 18 which form the supporting structure for the roof 43. The loading rail 24 connects assembly area 27 with the interior of circular magazine 14 while the ramming rail 25 connects the launching area 26 with the interior of the magazine. Suitable blast closures 34 and 36 are located at the outer extremity of the rail passages to isolate the interior of the magazine from any blast effects.

Located centrally within the launching well 26 is a launching device 13, while a dud area 30, remote from the magazine 14, and common to both halves of the system, communicates with the launching well, through a blast door 35. The assembly area 27, adjacent the magazine 14, houses a turntable 40 which serves to turn the missiles for introduction to either magazine after assembly, or as herein after more fully explained, may be used to cross-feed missiles from the magazine illustrated to an identical counterpart magazine, not shown. A missile component receiving area 38 is provided externally of the assembly area 27 and communicates therewith through closure 39, through which missile components may be introduced into the assembly area where they are assembled and checked out in testing area 28. The missiles are then mounted on carriages or carts 30, FIG. 3, as will become clear as the description proceeds, and are introduced to the magazine through closure 34, across loading rail 24 and onto a magazine turntable 12. The turntable 12 is then rotated to select any desired cell for storage of the missiles 23. The missiles may be all of the same type, as illustrated, or may comprise a mixture of missiles having different characteristics. For example, the guidance system, propulsion unit and warhead type may be varied as desired so that a variety of types of missiles is stored in the magazine.

A control area 33 is located externally of the system proper and serves to house necessary control equipment, personnel, electrical power sources and the like.

Underneath the magazine 14 there is provided an empty cart stowage cellar 32, which as explained more fully hereinafter, serves to store empty missile carrying carts after the missiles are launched.

It should be noted that the missiles 23 are shown stowed with the warhead ends directed outwardly. This, it will be observed, places the most lethal part of the missile adjacent the widest portion of the safety barrier

22 separating each reinforced concrete cell 15. This feature is primarily a safety feature so that should one or more of the stowed missiles explode prematurely, the detonation will be contained in as small an area as possible. In this connection, it should be noted in passing that the roof of the cells 15 may be constructed of any material which will provide a relatively soft structure, such, for example, as a sand barrier, to aid in restricting the premature detonation of a missile to as local an area as possible.

Since the assembly area 27 with its rotatable turntable 40 is advantageously located between the magazine 14 and its counterpart, should equipment fail in one half of the system, it is possible to cross feed ready missiles from one magazine to the other. For example, if a casualty occurred in the launching device 13 of the illustrated system half, missiles from magazine 14 could be transferred via the assembly area turntable 40 to the operative launcher system half, not shown. It is obvious that the flexibility and reliability of the overall launching system is considerably enhanced by this feature.

Referring now to FIG. 2, a ready missile 23 is illustrated as stowed within a cell 15. The missile is mounted on cart 30 which rests on feeder rail 20. The cell is surrounded by the outer wall 11, a roof 43, which as previously mentioned, may be padded with a non-frangible or blast attenuating material, and the runway or floor 45. The blast door 17 is shown in a closed position and another missile, illustrated in phantom, is shown in the position it would occupy upon magazine turntable 12. The pivot post 19 of the magazine turntable 12 may if desired serve as a central support for the roof 43 as well as the center of rotation of the magazine turntable. Within the magazine turntable 12 is carried an extendable chain ram 42 which is operated by a hydraulically driven sprocket 44. Any conventional extendable chain ram may be used, such as the one disclosed in U.S. Patent 2,779,246, and rammer in itself, forms no part of this invention.

A pair of circular tracks 55 supported by the roof 43 serves to carry an electrically driven cable drum 54. The circular tracks extend peripherally around the magazine turntable area, just inside the cell doors 17, so that the cable drum may be positioned upon the tracks adjacent any selected missile stowage cell. The cable drum 54 carries a hook 56 which is engaged in a loop or pad eye connected to the top of each closure 17 (not shown) to hoist the closure to a closed position after the cell is loaded. In order to open the cell, the turntable 12 is rotated to align itself with the selected cell. A circular guide ring 58, also continuous around the periphery of the turntable area, serves to guide the end of the turntable remote from its pivot post during its rotation by supporting turntable roller 71. Upon proper alignment with the selected cell, a hole in circular rail 58 registers with a plunger 60 positioned in a fluid actuated cylinder 59 which is carried on the underside of turntable 12.

Upon actuation, plunger 60 of cylinder 59 is extended through the registering hole in circular rail 58, to lock the turntable in proper position, and further extension of the plunger 60 causes deflection of the lever 61 so that through linkage 49, latch 57 is retracted from beneath door catch 50. Gravity then acts upon door 17 causing the door to fall into door pit 51. A safety door buffer 52 is positioned at the bottom of the pit to cushion the impact. During door descent, cammed surface 76 engages cam roller 77 to move the latter to the left thereby moving pivoted link 75 and rod 74 to the right. This movement actuates overcenter link 73 to the right around its pivot 79, moving support 72 to the right and downwardly out of engagement with the underside of missile 23. Thus missile 23 is released so that it may be extracted from its cell.

In loading a missile into a stowage cell 15, the door 17 is opened and the missile is rammed from turntable 12 through the open door up into the cell. The missile cart

80 (see FIG. 3) rides onto the feeder rail 20 to its stowed position. The hoisting hook 56 is engaged into a pad eye on the door 17 and the door is raised. On closing the door 17, cammed surface 76 again engages cam roller 77, which in this instance, moves the cam roller to the right, which action, through link 75, pushes rod 74 to the left. This pivots overcenter link 73, left around pivot 79, and through its action, positions support 72 underneath the forward section of the missile 23 and in supporting engagement therewith. Forward support 72 is provided so that long periods of stowage will not cause the forward section of the missile to sag due to its unsupported weight.

When the door 17 is fully closed, the door catch 50 is again engaged by latch 57. Just prior to closing the door 17, pressure in hydraulic cylinder 59 is partially released allowing catch 57, which may be spring loaded, to engage catch 50. The hydraulic cylinder 59 which had previously been partially unloaded so as to release lever 61 from the influence of plunger 60 is now fully retracted, thus retrieving the plunger 60 from its locking position extending through circular guide ring 58 and the turntable is free to rotate to any position, the cell having been loaded with a ready missile. As previously mentioned the turntable roller 71 merely serves to aid the turntable in rotating on the top surface of circular guide ring 58.

The sequence of operation during the loading of a cell proceeds as follows: The arrival of the missile carrying turntable 12 at a given cell position is followed by activation of hydraulic cylinder 59, causing projection of the plunger 60 to lock the turntable in that position on the circular guide ring. Further projection of the plunger 60 causes a rocking of the linkage 61 to retract latch 57 from engagement with catch 50. The door drops to the open position and through cam 76 causes actuation of the push-pull rod 74 which results in displacement of the forward support 72 thereby releasing the missile for retraction from its stowage cell.

In FIG. 3 there is shown a missile 23 suspended over a typical missile-carrying carriage or cart 80 to more clearly illustrate the structural relationship of parts. As is usual in larger missiles, a set of handling lugs 65 is affixed to the booster section of the missile. These lugs serve to facilitate handling the missile in all the operations required prior to launching. The after lug is normally T-shaped and positioned on the longitudinal axis of the missile while the forward lugs are normally attached one on each side of the booster section. When such is the case, the surface of the carrying cart 30 is preferably provided with keyways 66 adapted to receive their respective handling lugs. Suitable latching means 67 are preferably provided for firmly securing the missile to the cart. The latch shown, which, it should be understood, is merely illustrative of one suitable type of latch, has two positions, open and closed, either of which is maintained positively by engaging resilient pin 68 in either of holes 69 or 70. Shoulder 78 provides a positive stop against which forward lug 65 is abutted before closing latching means 67.

The missile 23 is placed on the cart 80 in the assembly area 27 with handling lugs 65 engaging their respective keyways 66 and latched in place. A vane 100 is then cocked, as by means of a tension spring 99, to cooperate with the launching device, as will be explained hereinafter, to remove the forward portion of the cart from the trajectory path of the missile on launching.

The cart wheels 98 run on the inner surface of loading rail 24 (as is also the case with the other rails of the system) as shown. Each cart used in the system is provided with a recess 97 on each end in which is positioned a cam block 113 which is engaged by the rammer hand 96 to pull the cart. The rammer hand 96 is carried by the working extremity of extendable rammer chain 42 while the rammer drive sprocket 44 is carried interiorly

of the magazine turntable 12 (FIG. 2). The rammer hand is so shaped as to allow it to act to pull cam block 113 with its inner face, while the lower surface of the hand is adapted to permit it to push against the lower surface of the cart. A release button or detent 114 is reciprocally mounted in cam block 113 and may be actuated in any desired manner to release or disengage rammer hand 96 from cam block 113.

Referring now to FIG. 4, the launcher 13, located centrally in the launching pit 26, is shown in loading position with a missile in place. A pedestal 88, mounted on launching pit floor 46 carries trunnion support 87 and allows train of the launcher in conventional fashion. A yoke 86, rotatable on the trunnions, is integral with yoke extension 85 and permits conventional elevation of the launcher in response to firing orders.

To load a missile, the launcher 13 is trained to alignment with rammer rail 25 and elevated to place launching rail 82 in horizontal relation. A substantially continuous path for cart travel is thus provided from rammer rail 25, through its extension 31, across fixed rail spur 112 onto launcher rail 82. The cart is preferably secured to the launcher rails by suitable latching means not shown. For purposes of clarity, the launching well door 36 is not shown in FIG. 4.

In order to load the missile, launching rail 82 is supported horizontally by floating element 83 which is integral therewith. Floating element 83 is pivotally connected to yoke extension 85 by means of pin 84. The forward end of element 83 is slidably supported by link 103 connected to roller 104 which bears against the upper surface of slot 105. The bottom end of link 103 is pivotally connected to yoke 86. A push-pull rod 102 is pivotally pinned to the middle of link 103 at one end and connects to a link 101 at its other end. Link 101, in turn, is pivotally connected midway of its length to floating support 83. At its extremities, link 101 is acted upon sequentially by spring loaded vane 100 and reset plunger 108.

When the missile 23 is to be fired, the missile is preferably connected, as is conventional to an external source of power, such as a backscratcher, (not shown) to arm the booster, warm up electronic components, and the like. The launcher is trained and elevated as desired and the missile is launched by detonating the booster.

It has been discovered that in launching missiles, it is desirable to remove the launching rails from the trajectory path of the missile substantially immediately after the firing of the missile. This practice is followed in order to prevent the missile handling lug on the after end of the missile from striking the forward part of the launching rails and thereby canting the missile into an undesirable trajectory path or attitude of flight.

In the instant invention, the missile is preferably fired directly from the carrying cart 30. However, by means of the launcher mechanism disclosed, the cart can be pulled down out of the projected missile path to avoid the undesirable effects outlined above.

Just prior to launching, the latching means 67 should be opened to allow the missile lugs 65 to pass through keyways 66 without interference. As the missile is launched and travels forwardly, the spring loaded vane 100 is released from contact with the underside of the booster casing and, due to its spring biasing, it rotates clockwise, as viewed in FIG. 4, to thereby strike link 101. The link 101 is rotated counterclockwise, FIG. 4, moving push-pull rod 102 to the right. This rocks link 103 clockwise and consequently roller 104 acting on slot 105 pulls floating element 83 down. Cart 30, carried on rail 82 which is integral with floating element 83, is pulled down at the same time allowing the missile to leave the launcher without interference from any of the associated launcher structure. The cart, of course,

remains on the launcher rails, and must of necessity be removed to reload the launcher.

The launching well door (not shown), closed during firing, is opened to reload the launcher. The launcher 5 is again trained to alignment with the rammer rail 25 and elevated to cause fixed rail spur 112 to align with spur extension 107 of empty cart track 47. The empty cart track 47, as shown, leads down under the level of the rammer rail 25 and the magazine floor 45. The 10 empty cart track 47 leads to empty cart stowage cellar 32 (FIG. 1) in which the carts are stowed till again required for use.

Simultaneously with the alignment of fixed rail spur 112 with spur extension 107, reset plunger 108 registers 15 with cylinder 109 formed in support housing 115. Cylinder 109 is connected to any suitable source of pressurized fluid so that reset plunger 108 may be forced to the left into cylindrical cavity 111 as shown in FIG. 4. This action is transmitted through push-pull rod 102 to 20 reposition link 103 in its normal position thereby raising the forward portion of floating element 83. If the cart has been secured to the launcher rail 82, as mentioned hereinbefore, these securing means should be released so that the empty cart, under the influence of gravity, rolls 25 down the launcher rails 82, across spur extension 107 and onto empty cart track 47 whence it rolls down to empty cart cellar 32 for stowage.

To lock the launcher in load position the launcher is 30 slightly depressed until a spring loaded detent 110, also carried in support housing 115, enters cylindrical cavity 111, which is now empty due to the movement of reset plunger 108. The launcher is now clear and locked in load position with the launcher rail 82 horizontal and ready for receipt of another rammed missile.

To load another missile the magazine turntable is 35 rotated to select a cell in which is stowed the desired type missile. The door is dropped, as aforementioned, the rammer hand is run out to pull a carted missile onto the turntable. The turntable is then rotated to alignment with rammer rail 25 and the cart with its missile is rammed across the rammer rail onto the previously prepared launcher rail.

Should a missile booster fail to detonate or for any 40 other reason should a missile be determined to be a dud 45 it is removed from the launcher to dud area 30. In such an event, the launcher, is trained and elevated to alignment with suitable rails within the dud area, and doors 35 and 36 are opened to permit the rammer 42 to push the cart carrying the dud from the launcher to the dud area. Suitable dud removal doors may be provided at the exit side of dud area 30 to facilitate removal to a 50 remote area for disposal.

The above-described system, as has been mentioned, 55 is approximately one half of an integrated launching system. The same operations may have been performed simultaneously or sequentially at the counterpart units of the system half, not illustrated. Thus it will be understood that missile salvos of two missiles or single coordinated or uncoordinated fire from each launcher is 60 possible. Also, because of the ease of selectability of the stowed missiles from the roundhouse magazine, it is 65 obvious that different types of missiles can be selected for fire to accomplish different purposes. It is possible, for example, to fire a ram jet powered, air-to-air missile with a conventional warhead from one launcher at the same time with a completely different type missile from the other launcher. Also to be noted, is the magazine cross feed flexibility possible with the disclosed system 70 by the employment of both loading rails 24 and the assembly area 27 therebetween.

Obviously many modifications and variations of the present invention are possible in the light of the above 75 teachings. It is therefore to be understood that within

the scope of the appended claims the invention may be practiced otherwise than as specifically described.

What is claimed is:

1. A guided missile launcher movable in azimuth and elevation comprising:
rotatable base and trunnion means for providing variable azimuth positioning;
yoke means pivotally mounted on said trunnion means to provide variable elevation positioning;
launcher rail means including an aft end and a forward end, defined with respect to the respective ends of a missile mounted thereon, pivotally mounted at the aft end thereof to said yoke means and adapted to support at both ends thereof a missile on the launcher;
said launcher rail means having its pivotal mounting axis on said yoke means parallel to the pivotal mounting axis of said yoke means on said trunnion means; and
means responsive to the initial movement of a missile launched from the launcher for pivoting the forward end of said launcher rail means away from the missile.
2. A system for stowing and launching guided missiles comprising:
circular annular magazine means including a ramming compartment and a plurality of missile stowage com-

partments each extending radially from the center of said magazine means;
missile launcher means movable in azimuth and elevation adjacent the exterior of said magazine means; and
missile selector and rammer means rotatably mounted in the center of said magazine means for selecting and withdrawing missiles from said magazine compartments;
whereby said selector and rammer means, after selecting and withdrawing a missile from one of said stowage compartments, rotates until aligned with said ramming compartment and then rams the missile through said ramming compartment and onto said launcher means.
